(57) **CLAIM**

The ornamental design for a side ledge for aircraft, as shown and described.

DESCRIPTION

FIG. 1 is a perspective view of a side ledge for aircraft showing our new design;

FIG. 2 is a front view of the side ledge for aircraft of FIG. 1;

FIG. 3 is a left view of the side ledge for aircraft of FIG. 1; FIG. 4 is a right view of the side ledge for aircraft of FIG. 1; and,

FIG. 5 is a top view of the side ledge for aircraft of FIG. 1. In FIGS. 1-5, the broken lines shown in the drawings depict portions of the side ledge for aircraft that form no part of the claimed design.
